United States Patent Office.

JAMES P. LABAR, OF MILFORD, MICHIGAN.

Letters Patent No. 98,872, dated January 18, 1870.

IMPROVED SASH-STOP, AND HOLDER.

The Schedule referred to in these Letters Patent and making part of the same.

To whom it may concern:

Be it known that I, JAMES P. LABAR, of Milford, in the county of Oakland, and State of Michigan, have invented a new and useful Improvement in Sash-Stops, Elevators, and Fasteners; and I do declare that the following is a true and accurate description thereof, reference being had to the accompanying drawings, and to the letters of reference marked thereon, and being a part of this specification.

Figure 1 is a view of the arrangement of the stops and rib-guides in place, with the front of the window-case removed.

Figure 2 is a view of the roller, cord, and weight, in place for elevating the sash.

Like letters indicate like parts in each figure.

The nature of this invention relates to an improved method of securing the sash at any desired position, and locking the same, so that it cannot be opened from the outside.

The invention consists in the new and novel arrangement of its various parts.

In the accompanying drawings—

A represents a window-frame, with a portion broken out to show the internal arrangement of the working parts.

B is the lower and C the upper sash, in each side of which are cut suitable grooves to fit the rib-guides D, which are rigidly secured to one side of the frame, and to fit upon the opposite side the rib-guides E E', which are loosely pivoted at top, and fit into proper grooves in the window-frame.

F is a shaft, journaled into the frame, and, passing through the inner plate of the same, is provided with a knob, G, by means of which it is actuated.

Connecting-cords, H, chains, or other suitable devices are secured at one end to this shaft, while the other ends, passing over suitable sheaves or pulleys, I, are secured to the springs-tops O, which are fastened to the frame, and are provided with a projection or latch, a, which passes through the frame and the rib-guides E E', and engages with suitable holes in the side of the sash.

Upon one side of the latch is a small projection, b, which engages with a slot in the rib-guides E E', for the purpose hereinafter described.

K is a roller, so placed that it will revolve in the top of the frame; and

L is a cord, winding on the pulley d, to the lower end of which is secured a metallic weight, M.

The sash may be connected to said roller by means of cords, which wind or unwind on said roller; or the upper sash may be provided with a suitable piece of netting, N, secured to the top of the sash and to the roller, in such a manner that when the upper sash is lowered, it will unwind the netting from the roller, thereby preventing the entrance of mosquitoes or other insects.

The knob G should turn to the right to unlock the lower sash, and to the left to unlock the upper sash.

Rotating the shaft to the right or left, allows the window-sashes to be raised or lowered, for the latch a is withdrawn from its engagement with the edge of the sash, the projection b allowing this to be done without disturbing the rib-guides E E'.

Should it be desired to remove the sash, the shaft should be rotated a little further in either direction, when the projection b engages with the end of the slot in the guides, and withdraws it from the corresponding groove in the sash, when the latter may be removed.

The connection of the sash to the rollers should be such that it may be disconnected readily, when desired.

I am aware of the invention of Clark Shaw, patented January 29, 1861, and of A. H. Boyd, patented October 15, 1867, and claim no part of the invention of either of them.

What I claim as my invention, and desire to secure by Letters Patent, is—

The arrangement of the shaft F, knob G, cords H, pulley I, spring-stops O, and pivoted rib-guides E E', with the sashes B C, and frame A, when constructed and combined to operate substantially as herein described.

JAMES P. LABAR.
